(57) CLAIM

The ornamental design for a scrubbing sponge handle, as shown and described.

DESCRIPTION

FIG. 1 is a front elevation view;
FIG. 2 is a rear elevation view;
FIG. 3 is a left side elevation view;
FIG. 4 is a right side elevation view;
FIG. 5 is a bottom plan view; and,
FIG. 6 is a front left side perspective view thereof.
The broken lines represent environment of the scrubbing sponge handle that form no part of the claimed design.

1 Claim, 3 Drawing Sheets(56)
